BROKEN BLADE HACK SAW ATTACHMENT

Kenneth W. Horton, Troy, N. Y.

Application July 22, 1946, Serial No. 685,329

2 Claims. (Cl. 145—35)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to a novel attachment for association in a hack saw construction of the conventional adjustable type which permits use of a broken hack saw blade therein.

As is well known, the frame of conventional hack saws is adjustable in length to accommodate blades of varying lengths and it is usual to provide holes in the blades, one adjacent each extremity thereof, to receive spaced pins or projections of the frame whereby the blades are removably held in place. It is a common occurrence to have the blades break at some point intermediate these holes in which case the usable remaining part of the blade will obviously have but one hole therein so that it cannot then be held in the frame.

It is accordingly a principal object of this invention to provide an attachment or device adapted to be associated with the broken, holeless end portion of the blade so that the frame may then be adjusted to carry the blade. That is to say, the attachment here to be described is such that the broken blade is provided with this necessary second hole and may be reassembled to the hack saw in operative relation.

This is accomplished by providing a device which has both a perforated part to supplant the broken end portion of the blade and means whereby the device may be securely attached to the blade. In this way, the broken blades need not be cast away but are fit for continued use.

As will be shown, the attachment is easy to assemble and simple in form so as to be economical to manufacture.

The specific nature of the invention as well as other objects and advantages thereof, will clearly appear from a description of a preferred embodiment as shown in the accompanying drawings in which:

Fig. 1 is a side elevational view of a hack saw embodying the novel features of the invention;

Fig. 2 is a perspective view of the attachment of the invention; and

Fig. 3 is a sectional view on the line 3—3 of Fig. 1.

For convenience in description, there is shown in Fig. 1 a hack saw frame F of the conventional adjustable type. There is a pair of angular end members 2 and 4, one of which has its horizontal arm portion receivable in a suitable recess

2

or channel provided in the horizontal part of the other member.

The said arm of one of the parts, such as arm 2 may have spaced notches 6 therein for receiving one or more pins or rivets 8 provided on the other arm or part 4. In other words, the end members 2 and 4 may be moved inwardly or outwardly relative to one another as in a conventional hack saw construction, the relationship of notches 6 and member or members 8 depending upon the length of the particular blade being accommodated.

The lower ends of the leg parts of the frame members 2 and 4 are provided with receivers 12 and 14 for what will be here called pin-holding members 16 and 18. These latter parts 16 and 18 preferably take the form of longitudinally-extending, rod-like pieces and one of them, such as 18, will be threaded into a suitably threaded socket provided in a handle member 20.

The inner or adjacent end portions of both the members 16 and 18 have flattened surfaces 22 and 24. A pin 30 extends outwardly from each of these surfaces in slightly opposed or inclined directions and it is these pins 30 which receive the apertured ends of the blade, as will be described.

The pin-holding members 16 and 18 are movable longitudinally in their receivers as well as being tiltable therein. This capacity of the end members 2 and 4 to both tilt and move longitudinally relative to one another and the ability of the loosely-held rods 16 and 18 to do the same relative to the receivers 12 and 14 supporting the same, together with the fact that the handle is threaded into member 14, makes it possible to adjust the frame to a blade of the desired size and to readily place an unbroken blade on the pins. Then the handle may be rotated to tighten up the blade for use.

The device itself will now be described in detail.

There is a substantially flat plate member 40 which comprises a main body part 42 and an extension part 44. The extension 44 may be at either end of the body part 42 but is preferably more or less of a continuation thereof and in substantially the same plane therewith.

In any event, part 44 is formed to simulate an unbroken end portion of an ordinary hack saw blade B. That is to say, the extension 44 is somewhat elongated with respect to the body part 42 and is so arranged that, when the attachment is associated with the broken end of the blade in a manner to be explained, it will be

substantially a continuation of that blade and supplant the broken end portion so that the blade may be assembled in the hack saw.

In all cases, the extension part 44 is provided with a hole 46 therethrough which, when the blade B and the attachment of the invention are in assembled relation, will be longitudinally aligned with the usual hole found in the unbroken end portion of the blade, as shown in Fig. 1. As will be obvious, the assembled blade and attachment may be so disposed relative to the frame that the broken end of the blade is at either end of the frame since the hole 46 may receive either of the pins 30.

The body part 42 of the plate member 40 is provided with a cut or slot 48 which is preferably in the shape of an inverted U and the portion 50 of the material within this cut is adapted to be bent outwardly from the plane of the body part along the line of its connection therewith to form a lip. Thus the cut-out portion 50, when bent as stated, provides an upwardly-directed, V-shaped groove in cooperation with the other coplanar parts of the body, which groove, as will appear, acts as a seat for the broken end portion of the blade B with which it is assembled.

On the upper side of the body 42 of the plate member is a ledge-like portion 52 which extends at an angle thereto and at a distance above the upper marginal edge of the inverted U-shaped slot. The ledge portion 52 is provided with a threaded opening 54 therethrough angularly or parallel to the plane of body part 42, and is adapted to receive a screw member 56 which is arranged to have its lower end engage the broken blade with which the attachment is associated. Thus the device may be securely attached to the holeless end of a broken hack saw blade and the broken blade may be assembled in the hack saw ready for use.

I claim:

1. As a new article of manufacture, an attachment to supplant the broken end portion of a broken hack saw blade comprising, a substantially flat plate member including a body part and an extension part at one end thereof, said body part being provided with an inverted

U-shaped cut therein and the portion within the cut being bent outwardly from the plane of said body part to form a V-shaped groove for supporting the broken end of a hack saw blade, said extension part formed to the shape of an unbroken end of a hack saw blade and provided with an opening therethrough, a ledge-like portion extending outwardly from said body part above and in the same direction as said bent portion, said ledge-like portion being provided with a screw-threaded opening therethrough, and a screw-threaded member movable in said opening and adapted to engage the hack saw blade whereby the portion of the blade disposed in said V-shaped groove may be releasably held in place.

2. As a new article of manufacture, an attachment to supplant the broken end portion of a broken hack saw blade comprising, a substantially flat plate member provided with an opening therethrough adjacent one end thereof, a cutout portion which is bent outwardly from the plane of said plate member to provide a V-shaped groove, a ledge-like portion extending outwardly from said plate member above and parallel to the line of intersection of said plate member and said angularly extending cutout portion, said ledge-like portion being provided with a screw-threaded member movable in a threaded opening in said ledge portion, the axis of said opening extending at an angle to the plane of said plate member and adapted to engage the hack saw blade whereby the portion of the blade disposed in said V-shaped groove may be releasably held in an uniplanar position.
